Primary Examiner—Alan P. Douglas*Assistant Examiner*—Robin V. Taylor*Attorney, Agent, or Firm*—DeWitt Ross & Stevens S.C.[57] **CLAIM**

The ornamental design for a sprinkler, as shown and described.

DESCRIPTION

FIG. 1 is a perspective view of a sprinkler showing my design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The broken line showing of wires in FIGS. 1-7 and a sprinkler base in FIG. 1 are for illustrative purposes only and forms no part of the claimed design.
